GLUING MACHINE

Robert Minkow, New York, N. Y., assignor to
 Hobbs Sales & Service Station, Inc., New York,
 N. Y., a corporation of New York

Application October 27, 1937, Serial No. 171,369

6 Claims. (Cl. 91—51)

This invention relates to a gluing machine and has for its object to provide, in a manner as hereinafter set forth, a new and improved feed means for the work which is to have one face coated with glue or other adhesive material.

5 A further object of the invention is to set up, in a manner as hereinafter set forth, a gluing machine of that type including pick-offs and being provided with an improved position of the bar for supporting the pick-offs.

10 A further object of the invention is to provide, in a manner as hereinafter set forth, a gluing machine having an improved position of the guide roll for the work when the latter is being acted upon.

15 A further object of the invention is to provide, in a manner as hereinafter set forth, a gluing machine including a new and improved form of pick-off elements so constructed to facilitate and to expedite the continuous picking-off of the work

20 from the glue applying roller when the work is being acted upon, as well as permitting of said elements being conveniently mounted in and removed from active position when desired.

25 A further object of the invention is to provide, in a manner as hereinafter set forth, a gluing machine including a pivoted shiftable superstructure carrying a platform for the work and with the platform provided with an adjustable resiliently mounted work feed.

30 A further object of the invention is to provide, in the manner as hereinafter set forth, a gluing machine having a new and improved adjustable resiliently controlled doctor.

35 A further object of the invention is to provide, in the manner as hereinafter set forth, a gluing machine including pick-offs, each being in the form of suspended gravity lowering carriers so formed as to enable picker fingers to be selectively secured to the sides of its forward terminal portion or to permit of picker fingers being secured to both sides of said terminal portion.

40 Further objects of the invention are to provide, in the manner as hereinafter set forth, a gluing machine which is comparatively simple in its construction and arrangement, strong, durable, compact, readily assembled, very efficient in its use and comparatively inexpensive to manufacture.

45 To the above ends essentially and to those which may hereinafter appear, the invention consists of the novel construction, combination and arrangement of parts as will be more specifically referred to and illustrated in the accompanying drawings where there is shown an embodiment 50 of the invention, but it is to be understood that

changes, variations and modifications may be resorted to which fall within the scope of the invention as claimed.

In the drawings:

Figure 1 is a side elevation of a gluing machine 5 according to this invention,

Figure 2 is a fragmentary view in top plan,

Figure 3 is a fragmentary view in front elevation of the machine,

Figure 4 is a section on the line 4—4 in Figure 2,

Figure 5 is a diagrammatic view illustrating the operating mechanism for the machine,

Figure 6 is a section on the line 6—6 in Figure 4,

Figure 7 is a side elevation of a pick-off element,

Figure 8 is a top plan view of the pick-off element,

Figure 9 is a section on the line 9—9 in Figure 7,

Figure 10 is a front elevation of the form of pick-off finger, and

Figure 11 is a section on line 11—11, Figure 1.

The machine includes a base structure, generally indicated at 1, and a superstructure generally indicated at 2. The structure 1 provides a support for the structure 2 and when the machine is in position to be used, the structure 2 is arranged in superimposed relation with respect to the structure 1.

The structure 1 includes a hollow open top and closed bottom body part generally indicated at 4 and which provides a chamber 5 for the glue or other adhesive material. The structure 4 consists of a bottom 6, a pair of side walls 7, 8 of like form, a front wall 9 and a rear wall 10 which corresponds in height to the front wall 9. Each side wall has front and rear supporting legs 11, 12. The rear edge of a leg 11 is flush with the outer face of the wall 10. The forward edge of a leg 12 is flush with the outer face of the wall 9. The construction of but one side wall is shown and which is side wall 8.

Each side wall has an enlarged portion 13 provided with a cut-out 14 and a lengthwise extending passage 15 opening at its front at the front of structure 1 and at its rear end into the cut-out 14. Secured within the cut-out 14 near the rear thereof by the holdfast means 16 is a block 17 provided in its top with a rabbet 18. Each side wall rearwardly of block 17 is provided with a bearing 19. The rear terminal portion of the enlargement 13 is of angular contour and consists of a horizontally disposed leg 20 merging at its rear end into a vertically disposed leg 21.

15

20

25

30

35

40

45

50

55

The top edge 22 of leg 20 is horizontally disposed and is flush with the top edge of the bearing 19. The forward edge 23 of the leg 21 is square and vertically disposed. The rear end of edge 22 5 merges into the lower end of the edge 23.

Slidably mounted in each cut-out 14 is a bearing 24 having connected to the front thereof a forwardly extending adjusting bar 25 therefor. The rod 25 extends through the passage 15 and 10 projects forwardly from structure 1. The outer terminal portion of rod 25 is peripherally threaded, as at 26 and adjustably engaging therewith is an internally threaded and peripherally knurled adjusting nut 27 for the bar 25. Interposed between the forward edge of the wide wall and the nut 27, as well as surrounding the rod 25, is an abutment collar 28 for nut 27. Encompassing the rod 25 and interposed between the forward end wall of the cut-out 14 and the bearing 24 is a tensioning spring 29 for the latter.

Mounted in the rabbets 18 and anchored to the blocks 17 by the holdfast means 30 are scraper elements 31 of angular form. Each scraper element 31 extends inwardly from the block 17 to 25 which it is attached and consists of legs 32, 33 disposed at right angles to each other. The leg 32 extends transversely with respect to structure 1 and the leg 33 depends from the inner end of the leg 32 and is disposed at an inward inclination. 30 The elements 31 extend in opposite directions with respect to each other and are of a length whereby the leg 33 of one element 31 will be spaced from the leg 33 of the other element 31.

Extended in lateral relation with respect to one 35 side of the superstructure 2 and the side wall 9 of base structure 1 is an open bottom sectional housing 34 for a gear train 35 (Figure 5) including a pinion 36, a large gear 37, a pinion 38, a small gear 39 and a large gear 40. The housing 40 34 is formed of rear and front sections designated 40a, 40b respectively and which are secured respectively to the structures 1 and 2. The pinion 36 is the drive for the train and it is driven by a transmission shaft 41 to the inner end of which 45 is fixed said pinion. The shaft 41 extends into housing 34 and has its outer end provided with a drive pulley 42 therefor, which is operated by an endless transmission belt 43, driven from a pulley 44 on the shaft 45 of an electric motor 46. A 50 casing 47, secured to the section 40a of the housing 34, encloses the pulley 42 and the stretch of the belt 43 which passes around pulley 42. The latter is of greater diameter than pulley 44. The pinion 36 meshes with gear 37, the latter meshes 55 with pinion 38 and the gear 39 meshes with gear 40. The gear 37, pinion 38 and gear 40 are for the purpose respectively of operating one of the stub shafts 48 of a glue applying roll 49, guide roll 51 and one of the shafts 52 of a doctor roll 53. 60 The gear 37 is on the shaft 48; pinion 38 is on one end of roll 51; and gear 40 is on shaft 52. The gear 39 is fixed to the stub shaft 48 which carries gear 37 and disposed outwardly with respect to the latter.

65 The stub shafts 48 are mounted in the bearings 19 and the one carrying gear 37 extends laterally from the bearing 19 mounted in side wall 7. The position and mounting of the roll 51 will be referred to. The stub shafts 52 are mounted in the bearings 24 and that one which carries gear 40 extends laterally from the bearing 24 in the wall 7. The latter has secured to its outer face a combined bearing and spacer block 54 through 70 which passes the extended stub shaft 52. The

block, however, may be an inward continuation of the hub of gear 40.

The glue applying roll 49 is of greater diameter than the doctor roll 53 and the latter is of greater diameter than the guide roll 51. The roll 49 is suspended in the chamber 5 by the stub shafts 48 and is of less length than the roll 53. The latter is suspended in the chamber by the stub shafts 52 forwardly of and in close proximity to the roll 49. The ends of the roll 49 are spaced equi-distant from the side walls 8, 9. The roll 53 has its ends extend equi-distant with respect to the ends of the roll 49 and are spaced equi-distant from the side walls 8, 9. The scrapers 30 bear against the ends of the roll 49.

15 The superstructure 2 includes a pair of up-standing side cheeks 55 of like form. Each side cheek comprises a rear part 56 and a forward part 57 of materially less height than the part 56. The latter is formed with a rounded lower 20 rear corner 58, a vertical rear edge 59, horizontal bottom edge portions 60, 61 connected by a vertical shoulder 62 and with the edge portion 60 arranged above the edge portion 61, a horizontal top edge 63 of less length than the combined 25 length of the edge portions 60, 61, and a downwardly extending forwardly inclined front edge portion 64 merging at its lower end into a vertically disposed front edge portion 64a. The front edge of part 56 is of less height than the rear 30 edge of the latter. The part 57 is of oblong contour and of greater length than part 56. The bottom edge portion of part 56 is flush with and forms a rearward continuation of the bottom edge 61 of part 57. The top edge 66 of the latter aligns 35 with the lower end of the edge portion 64 of part 56. The edge portions 64a of the parts 56 of the cheeks 55 provide a pair of aligning shoulders. Secured upon the top edges 66 of the parts 57 of the cheeks 55 is a table or platform 67 which abuts the shoulders provided by edge portions 64 and has the major portion of the length of its side edges flush with the outer side faces of the parts 57 of the side cheeks. The table 67 extends forwardly with respect to the parts 57 of the side cheeks and the front of base structure 1. The parts 56 of the side cheeks 55 are provided intermediate their ends with aligned notches 68 opening at the edges 63 of such parts.

The table or platform 67 is secured to the parts 60 57 of the cheeks 55 by the holdfast means 69 and it is formed with a rear portion 70 of reduced width but of a width greater than the length of the roll 49. The rear end of the part 70 of table 67 is beveled as indicated at 71 and is disposed in 65 close proximity to the periphery of the roll 49.

The structure 2 is pivoted at its rear end to the structure 1 and for such purpose the rear portions of the parts 56 of the side cheeks 55 are reduced as indicated at 72, and the legs 21 of walls 8, 9 are rabbeted as at 73. The reduced portions 72 are pivotally connected to the rabbeted portions 73 by pivot pins 74. The rounded shoulders 58 of the side cheeks provide clearance when the superstructure 2 is shifted relatively to the base structure 1 to open and close the chamber 5. The forward extended portion of the table 67 constitutes what may be termed a handle for elevating and lowering the structure 2 relative to the base structure 1.

70 The guide roll 51 is positioned over and in close proximity to the top of the glue roll 49 rearwardly of and in close proximity to the vertical median of roll 49. The guide roll 51 is mounted in the notches 68 of the parts 56 of the side cheeks 75

55. The guide roll 51 is maintained in the notches 68 by the retainers 74^a detachably secured to the top edges 63 of the parts 56 of the side cheeks 55 as at 75.

5 Arranged over and connected to the reduced portion 70 of the table 67 is an adjustable feed means 76 for the work. The length of the feed means 76 is less than the width of the portion 70 but greater than the length of the roll 49. The 10 feed means 76 consists of a bar 77 provided at its ends with a pair of oppositely extending apertured ears 78. The bar 77 (Figure 4) has a vertical rear edge, a flat top edge and a vertical front edge numbered 79, 80, 81 respectively. The edge 15 79 is of greater height than the edge 81. The upper ends of the rear and front edges align. The bar 77 includes a lower edge 82 shaped upon a segment of a circle extending downwardly and rearwardly from the lower end of edge 81 to the lower end of edge 79 whereby the said lower edge 20 82 is of beveled contour. Extending upwardly through the spaced aligned openings 83, in the portion 70 of the table 67, is a pair of upstanding threaded headed bolts 84 having their heads 25 85 abut the lower face of said portion 70. The bolts 84 pass through and project above the ears 78. Threadedly engaging with the portions of the bolts 84, which project above the ears 78 are flanged adjusting sleeves 86 for the bar 77. Surrounding the bolts 84 and interposed between the ears 78 and the portion 70 of table 67 are coiled tensioning springs 87 for bar 77. The lower end of the edge of bar 77 is disposed in close proximity to the edge 71 of portion 70 of table 67. The 30 springs 87 act as yielding suspensions for the bar 77 and normally hold the ears 78 against the adjustable sleeves 86. The tension of the springs 87 is adjusted by the sleeves 86 for the purpose of varying the distance between table portion 70 and 77. The work is passed between the lower side of edge 79 of bar 77 and the upper face of the portion 70 of table 67. The springs 87 act to 35 permanently maintain the bar 77 and table 70 in spaced relation.

45 The side walls 8, 9 of the base structure 1 are connected together by a pick-off support in the form of a rod 89 having an intermediate portion 90 of circular cross section and a pair of flat end portions 91 which are anchored by the holdfast 50 means 92 against the upper part of the rear edges of the legs 21 of the walls 8, 9. The portion 90 of rod 89 is arranged between the rear ends of the walls 8, 9.

Removably mounted on the portion 90 of rod 55 89 are spaced gravity lowering pick-offs 93 disposed in spaced relation and of like form. Each pick-off consists of a carrier 94 formed of a substantially inverted U-shaped clutching part 95 which merges at the lower end of its forward side 60 96 into the top of the rear end of a curved weighting part 97 merging at the top of its forward end into the rear end of a substantially segment shaped head 98, formed with a pair of transversely extending spaced threaded openings 99, 100 which are disposed on a line extending diagonally of the head 98 from the lower forward corner 101 of the latter. The opening 100 is arranged in proximity to corner 101. The opening 99 is arranged forwardly of the vertical median 70 of the head. The thickness of the part 95 is materially less than the thickness of the part 97. The width of the part 95 corresponds to the width of the rear portion of the part 97 (see Figs. 4 and 8). The latter has its forward portion gradually decreasing in width from its rear portion to

the head 98. The width of the latter corresponds to the width of the point of mergence between the parts 97, 98 and part 98 is disposed centrally with respect to the part 96 and the rear portion of the 15 97. There is associated with each carrier one or more picker fingers 102 of substantially trapezium contour. Each finger has its end edges 103, 104 feathered. Each finger has its top edge 105 of less length than the bottom edge 106. The edge 103 extends at an inward inclination from one 20 end of edge 106 to one end of edge 105. The edge 104 extends at an inward inclination from the other end of edge 106 to the other end of edge 105. Each finger is formed with a pair of horizontally aligned spaced openings 107, 108 arranged adjacent opposite sides of the transverse median thereof. When the pick-off includes a single finger, the latter may be selectively secured to either one of the sides of the head 98. When the pick-off includes two fingers they are secured to opposite sides of the head 98. When a finger is secured to a head it is disposed at an angle with respect to and projects downwardly from the head. A finger is detachably coupled or secured to a head by a headed screw 109 passing through an opening 107 or 108 and threadedly engaging in an opening 99 or 100. The length of the shank of the screw 109 is such that when securing a finger in position, the shank will extend only a part of the length of opening 99 or 100. The 30 openings 99, 100, 108, 107 are provided to enable the adjusting the position of the finger relative to head 98. The weighting part of the carrier tends to maintain the lower forward corner of the finger upon the top of the glue applying roll 35 rearwardly of the guide roll.

The chamber 5 may be termed a glue or adhesive reservoir. The doctor roll 53 is resiliently disposed relative to the front of the glue applying roll 49. The table 67 provides a work support 40 and also functions as a closure for the major portion of the top of chamber or reservoir 5. The scrapers 30 act upon the ends of roll 49. The feed means 76 is vertically adjustable to compensate for varying thickness of the paper or 45 work to be acted upon and is disposed in such relation to the roll 49 to provide for application of the glue throughout the surface of the work to be acted upon. The doctor roll functions to limit the amount of the glue on that portion of the 50 periphery of roll 49 employed to apply the glue to a surface of the work. The blocks 17 are so arranged relative to bearings 19 to hold the latter tight. The superstructure 2 when in superimposed position relative to the base structure 1 holds the doctor roll bearings down. 55

The intermediate portion 90 of the support 89 is of slightly greater diameter than the distance between the front and rear of the inverted U-shaped clutching part 95 of carrier 94 whereby 60 the support 89 and carrier 94 are clutched together by a snapping action to prevent their separation when the machine is operating, but the clutching is such as to arrest the tendency of the pick-off continuously bearing on the glue 65 applying roller.

What I claim is:

1. In a gluing machine, a horizontally disposed work supporting table adapted to have its rear end disposed in close proximity to an adhesive applying roll for the work, a bar disposed transversely of the inner end of said table and having its rear side aligning with the rear edge of the table, said bar formed at its ends with oppositely disposed apertured ears, a pair of 70 75

- threaded headed bolts extending upwardly through the table in proximity to its rear edge, the heads of said bolts bearing against the lower face of the table, said bolts extending through and projecting above said ears, adjusters for the bar threadably engaging with the bolts above and bearing on said ears, and coil springs encompassing said bolts and interposed between said ears and the upper face of the table.
5. In a gluing machine of that type including an adhesive applying roll, the combination of a base structure for revolvably supporting said roll and being formed with an adhesive reservoir into which said roll extends, a transverse bar secured to the rear part of said structure, forwardly directed carriers each including a weightier intermediate part, an inverted U-shaped rear part for seating on said bar and a head extended forwardly from said intermediate part, picker fingers adapted to be selectively positioned against opposite sides of the head and positioned against both sides of the head, said heads and fingers having coacting means to provide for adjustably positioning the fingers relative to the heads, and means for anchoring the fingers to the heads in selected and adjusted positions.
6. In a gluing machine of that type including a revoluble adhesive applying roll, a work supporting table adapted to have its inner end positioned in proximity to and arranged below the top of said roll, a bar disposed transversely over and arranged in spaced relation to the upper surface of the table, said bar having its rear end surface aligned with the rear edge of the table, upstanding suspension springs for the bar bearing at their upper ends against the lower surfaces of the end terminal portions of the bar for maintaining the latter in spaced relation to the upper surface of the table, and a carrying structure for said springs connected to the table and including adjustable means bearing on the upper surface of the bar for adjusting the tension of the springs to vary the distance between the lower surface of the bar and the upper surface of the table, and said means and springs coacting with the bar for maintaining the latter in its adjusted position.
7. In a gluing machine of that type including a revoluble adhesive applying roll, a base structure for revolvably supporting said roll and being formed with an adhesive reservoir into which said roll depends, said structure having the upper portion of its rear cut out, a transverse supporting bar arranged in said cut out and secured to said structure, forwardly directed carriers, each including a depending weighting intermediate part, a rear end part extended upwardly from the top of the rear end of the intermediate part for detachably mounting on said bar and a front end part in the form of a head extended forwardly from the top of the front end of said

intermediate part, work pick-up fingers correlated with said roll for removing the work from the latter and adapted to be selectively positioned against a selected side and positioned against both sides of a head, and means coacting with said heads for detachably anchoring the fingers in selected and in adjusted positions relative to the heads.

8. In a gluing machine of that type including a revoluble adhesive applying roll, a base structure for revolvably supporting said roll and being formed with an adhesive reservoir into which said roll depends, a supporting bar disposed transversely of the rear of the upper portion of and secured to said structure, carriers disposed in the upper portion of said structure, each carrier formed of a one-piece body including a rear part for detachably connecting the carrier to said bar, a front part in the form of a head and an intermediate part depending from said other parts, said intermediate part providing a weighting means for the carrier and having its sides disposed in offset relation with respect to the sides of the head of a carrier, adjustable work pick-up fingers correlated with said roll for removing the work from the roll and adapted to be positioned against at least one side of a head, and means providing for the adjustment of the fingers relative to the heads.

9. In a gluing machine of that type including a revoluble adhesive applying roll, a base structure for revolvably supporting said roll and being formed with an adhesive reservoir into which said roll depends, a supporting bar disposed transversely of the rear of the upper portion of and secured to said structure, carriers disposed in the upper portion of said structure, each carrier formed of a one-piece body including a rear part for detachably connecting the carrier to said bar, a front part in the form of a head and an intermediate part depending from said other parts, said intermediate part providing a weighting means for the carrier and having its sides disposed in offset relation with respect to the sides of the head of a carrier, adjustable work pick-up fingers correlated with said roll for removing the work from the roll and adapted to be positioned against at least one side of a head, means providing for the adjustment of the fingers relative to the heads, said fingers being in the form of a frustum of a triangle and provided with a pair of spaced horizontally aligned openings, each of said heads being formed with a pair of spaced diagonally aligned threaded openings for normally registering with the openings of a finger, and the said means passing through at least one of the openings of the fingers to threadedly engage with the wall of at least one of the openings in the heads.

ROBERT MINKOW. 60
